[57] CLAIM

The ornamental design for stylized boxing game apparatus, or similar article, substantially as shown and described.

DESCRIPTION

FIG. 1 is a plan view of a stylized boxing game apparatus, or similar article, showing my new design,

FIG. 2 is a side elevational view thereof;

FIG. 3 is an exploded side elevational view of a corner portion thereof;

FIG. 4 is an exploded perspective view of one top and spinner;

FIG. 5 is a vertical sectional view of the arena, taken on the line 5—5 of FIG. 1.
